DESIGN FOR A DRESS ENSEMBLE

Germaine Monteil, New York, N. Y.

Application January 21, 1941, Serial No. 98,205

Term of patent 3½ years

To all whom it may concern:

Be it known that I, Germaine Monteil, a citizen of the United States, residing in New York city, in the county of New York and State of New York, have invented a new, original, and ornamental Design for a Dress Ensemble, of which the following is a specification, reference being had to the accompanying drawing, forming part thereof.

Figure 1 is a front view of a dress ensemble, showing my new design;

Figure 2 is a rear view of Figure 1;

Figure 3 is a front view of the dress member of the ensemble shown in Figure 1; and

Figure 4 is a rear view of Figure 3.

The characteristic feature of my design resides in the combination on the dress ensemble disclosed of the specific jacket member having a contrasting collar which matches the blouse and lower half of the two-toned girdle of the dress member in association with the specific fastening elements, all as shown.

I claim:

The ornamental design for a dress ensemble, substantially as shown and described.

GERMAINE MONTEIL.
